CURRENT CONTROL SYSTEM

Walter S. Thompson, Los Angeles, Calif., assignor to Radio Corporation of America, a corporation of Delaware

Application March 24, 1942, Serial No. 436,006

10 Claims. (Cl. 179—100.3)

This invention relates to electrical current transmission systems and particularly to a control system for the recording of sound or for radio transmitters. In sound recording for motion pictures, the means provided in accordance with the invention will control the noise reduction action, while in radio broadcasting the invention is applicable to the control of the carrier current amplitude.

Practically all present day sound recording systems embody noise reduction to increase the film volume range by increasing the lower recordable limit. Several forms of noise reduction are in general use, one type being applicable to variable area sound tracks wherein the portion of the sound track area not utilized by the modulations is made opaque, and another type being applicable to variable density sound tracks wherein the average density of the track is varied in accordance with the signal level.

In substantially every form of noise reduction, a rectifier is employed for obtaining a direct current proportional to the level or volume of the signal. This direct current is then used either to operate noise reduction elements in the form of shutters to vary the light impressed on the film, or to vary the average value of the intensity of the light impressed upon the film by suitable means.

In applying the noise reduction action, it is desirable that the clipping of the first peaks of the signal modulations, particularly when the beginning of the signal has a considerable amplitude, be prevented, while subsequently securing the maximum amount of noise reduction during steady state conditions. That is, in the case of variable area sound tracks, the boundary or boundaries of the opaque portions should substantially coincide or follow the peaks of the modulations, the amount of separation between the opaque portion and the peaks being known as "margin". Thus, what is desired is a low margin to provide adequate noise reduction during steady state conditions, and a fast action at the beginning of the signal to avoid peak clipping.

The present types of noise reduction systems which are fast enough to avoid peak clipping have an undesirably large margin, while the low margin systems are slow acting and will clip the peaks at the beginning of the sound waves. The present invention is directed to a system which will provide a zero or substantially zero margin, while producing the necessary rapidity of action. This is accomplished by a series arrangement of an expander and compressor units ahead of the noise reduction amplifier, each

unit being timed in a manner to be described hereinafter.

The type of compressor employed may be as shown in Singer Patent No. 2,255,683, of September 9, 1941. Although this patent discloses a compressor, it is only necessary to interchange the output leads from the rectifier to obtain an expanding action, as is well known in the art. The present invention may thus employ two such units in series prior to the noise reduction amplifier, the units being connected into a standard sound recording channel either after the recorder amplifier or between the regular signal compressor and the recorder amplifier. For radio broadcasting, the invention may be employed to vary the amplitude of a carrier in accordance with the variations in the signal strength to insure that the carrier will at all times accommodate the peaks of the broadcast signal.

10 The principal object of the invention, therefore, is to provide means for controlling a current as a function of the volume of a signal.

Another object of the invention is to provide means for utilizing the action of a serial arrangement of an expander and compressor to control a characteristic or function of a signal current.

20 A further object of the invention is to provide means for controlling the noise reduction action of a sound recording channel so as to accurately follow the peaks of the signal.

Another object of the invention is to provide a sound recording channel with a fast-acting and low margin noise reduction system.

30 A further object of the invention is to provide means for operating the noise reduction shutters of a variable area sound recording system so as to follow the peaks of the recorded modulations.

40 Although the novel features which are believed to be characteristic of the invention are pointed out with particularity in the claims appended herewith, the manner of its organization and the mode of its operation will be better understood by referring to the following description read in conjunction with the accompanying drawing forming a part hereof, in which:

Figure 1 is a block diagrammatic drawing showing a standard sound recording channel embodying the invention.

Fig. 2 is a partial section of a sound track, illustrating the operation of the invention, and,

Fig. 3 is a graph showing the timing operation of the serially arranged expander and compressor units of the invention.

Referring now to Fig. 1, a microphone 5 feeds

a preamplifier 6 connected to a mixer 7 and an amplifier 8, the latter feeding a regular signal compressor unit 9 as disclosed and claimed in the above-mentioned Singer patent. The output of the signal compressor is then fed into a recorder amplifier 12 connected to the galvanometer 13 of the sound recorder shown diagrammatically. Connected across the output of the signal compressor is a control expander 15 connected to a control compressor 16, the output of the latter being fed to a noise reduction amplifier 17 connected to a noise reduction unit 18 having shutters 19.

The sound recording portion of the system is the well-known variable area type in which a light from a lamp 20 is collected by a lens 21 and projected upon an aperture mask 22. The light passing through the aperture of the mask 22 and past the shutters 19 is projected by a lens 25 upon a mirror of the galvanometer 13, from which it is reflected to a slit mask 26 through a lens 27. The light emerging through the slit of the mask 26 is projected on the film 30 by projection lenses 31. Such a sound recording system is disclosed and claimed in U. S. Patents Nos. 2,102,776, 2,102,777 and 2,102,778.

The above-described film recorder will produce a bilateral variable area track well-known in the art, a portion of which is shown in Fig. 2, to which reference will now be made. During the periods of no signal short light beams will be projected to the film 30, as shown by the bias lines x of the sound track of the type suitable for reproduction in theaters. The outside boundaries of the bias lines are, of course, produced by the edges of the shutters 19, the shutters moving outwardly and inwardly to accommodate the modulations as the signal increases and decreases in amplitude, respectively. As illustrated by the full shutter lines, it will be noted that the shutter movement is such that the first two peaks at the beginning of the signal are clipped before the shutters reach point c of their steady state condition. However, from then on, the action is such as to provide a zero or substantially zero margin until the amplitude increases, the shutters clipping the first peak of the increased signal until point e is reached. Thereafter, the noise reduction shutters just accommodate the peaks of the signal during the next steady state condition.

To provide a sufficiently rapid noise reduction action to avoid clipping the peaks of the beginning of a signal or signal amplitude increases, it will be necessary to have the shutters move as shown by the dotted line, which however, provides too large a margin during steady state conditions. Such a large margin is undesirable because of the introduction of noise by the clear portion of the film between the dotted line and the solid line of low margin shutter action. It is realized, therefore, that the preferred action is a combination of the full and dotted lines as shown by the dot and dash line connection therebetween. By this combination of actions, the shutters will move fast enough at the beginning of or during an increase in a signal so as to clear the first peaks as shown by the dotted line, slow down as shown by the dot and dash lines to provide a substantially zero margin as shown by full lines. With the invention, this desired result may be accomplished.

To explain how the shutter action is obtained, reference is made to Fig. 3, wherein is charted the gain of each individual expander and com-

pressor, as well as the resulting gain of the combination with respect to time. The noise reduction amplifier will first be adjusted to provide a substantially zero margin for steady state conditions as shown by the full shutter lines in Fig. 2. The expander-compressor combination will then be adjusted to have a zero gain during these steady state conditions, wherein the amount of compression equals the amount of expansion. The starting rate for each particular compressor and expander will now be adjusted as shown by curves A and B in Fig. 3, curve A being the expander characteristic and curve B the compressor characteristic. Starting at the point a corresponding to point a in Fig. 2, at the beginning of a signal, the gain of the expander is adjusted to rapidly increase with increasing signal level while the gain of compressor is adjusted to slowly decrease with the same increase in signal level.

The result is a rapid increase in overall gain of the combination, as shown by curve C, thus producing a rapid shutter action as shown in Fig. 2, between points a and b . At point b in Fig. 3, where the distances g and g' are equal the overall curve C begins to drop, which shows a decrease in overall gain to point c where the distances h and h' are equal and the compression balances the expansion. The normal low margin adjustment of the noise reduction amplifier is then effective. This normal noise reduction action will continue until there is a further increase in signal as shown by the continuation of curves A, B and C, points d and e in Fig. 3 corresponding to points d and e in Fig. 2, the distance i being equal to distance i' showing equal compressor and expander actions. By causing the output of the noise reduction amplifier to respond in accordance with curve C the shutter or shutters or other noise reduction element will follow the combination curve in Fig. 2, and just clear the peaks of the waves.

The time axis in Fig. 3 does not exactly correspond to the time of film movement between points a and e in Fig. 2 since the length of portion c of curve C and corresponding portions of curves A and B in Fig. 3 are not related to the length of film between the two points labelled c in Fig. 2. As the gain of the combination of compressors 15 and 16 is zero during the time when the signal amplitude is constant, portion c in Fig. 3 was not extended beyond the length shown. However, the portions of Figs. 2 and 3 where the amplitude is increasing may be considered to correspond on a similar time basis.

In the above described example, it is to be noted that no closing action is shown. Although the gain of the combination expander-compressor is preferably zero during the closing time and the noise reduction unit 17 has the normal slow rate of closing, as shown in Kreuzer Patents No. 2,224,914, of December 17, 1940, and No. 2,260,717, of October 28, 1941, a variation in closing time may be easily obtained if desired by providing each unit with a different closing adjustment.

It is also to be understood that although the expander and compressor are shown as self-contained units, a single rectifier could control the variable gain amplifiers in both units through different timing circuits.

I claim as my invention:

1. In a current control system, the combination of a source of electrical currents, means for obtaining an average current proportional to the

amplitude of said currents, and means for varying said average current to follow the peak values of said electrical currents during increases in amplitude of said currents.

2. A current control system in accordance with claim 1 in which said last-mentioned means comprises an expander-compressor combination having a substantially zero overall gain for said electrical currents of constant amplitude, said compressor having a different operating time from that of said expander for current variations increasing in amplitude.

3. A current control system in accordance with claim 1 in which said last-mentioned means comprises an expander-compressor combination having a substantially constant gain for said electrical currents of constant amplitude, said expander having a faster operating time from that of said compressor during increases in amplitude of said electrical currents.

4. A sound recording system comprising a source of signals to be recorded, means for modulating a light beam in accordance with the instantaneous amplitudes of said signals, means for deriving an average current having a certain proportionality with respect to the amplitude of said signals for further modulating said light beam, and means intermediate said source of signals and said last-mentioned means for affecting said proportionality of said average current with respect to the amplitude of said signals during amplitude increases therein.

5. A sound recording system in accordance with claim 4 in which said intermediate means comprises an expander-compressor combination having a substantially zero gain during steady state conditions of said signals.

6. A signal transmission system comprising a

source of signal currents, means for deriving an average current having a certain proportionality with respect to the volume variations of said currents, and additional means for varying said proportionality of said average current during amplitude increases in said signal currents.

7. A signal transmission system in accordance with claim 6 in which said last-mentioned means includes an expander having a rapid operating time and a compressor having a slower operating time, the combination effect of said expander and compressor for signal currents of constant amplitude being substantially zero.

8. A noise reduction system for recording sound on film comprising a rectifier for signal currents to be recorded, means for providing said rectifier with a certain predetermined operating time for increases and decreases in amplitude of said signal currents, and means feeding said rectifier for varying said certain predetermined timing of said rectifier during amplitude increases in said signal currents.

9. A noise reduction system in accordance with claim 8 in which said rectifier feeding means includes means for increasing the rapidity of the operating time of said rectifier during amplitude increases in said signal currents while maintaining said operating time as predetermined during steady state conditions.

10. A noise reduction system in accordance with claim 8 in which said rectifier feeding means includes a compressor and an expander connected in series, said compressor operating on signal increases at a slower rate than said expander, the combined gain of said compressor and expander being zero when transmitting currents of constant amplitude.
